UNITED STATES PATENT OFFICE.

THOMAS M. HARRIGAN, OF WOODSTOCK, VERMONT.

DEVICE FOR ELIMINATING BODY CAPACITY EFFECTS IN RADIO INSTRUMENTS.

Application filed December 20, 1922. Serial No. 608,089.

To all whom it may concern:

Be it known that I, THOMAS M. HARRIGAN, a citizen of the United States, residing at Woodstock, in the county of Windsor and

5 State of Vermont, have invented new and useful Improvements in Devices for Eliminating Body Capacity Effects in Radio Instruments, of which the following is a specification.

10 This invention relates to a device for eliminating body capacity effects in radio instruments, and has for its object to provide a device through the medium of which certain dials employed for adjusting portions of a radio instrument, particularly the condenser, may be rotated while tuning the instrument without the body of the operator influencing the instrument and thereby rendering it difficult to properly tune the

20 same.

Another object of the invention is to provide a device which may be employed in a manner to obtain a much more delicate adjustment of the dial and portion of the instrument associated therewith than is possible through the medium of the usual handle provided for the dial.

The invention consists in the combination and arrangement of parts set forth in the following specification and particularly pointed out in the claim thereof.

Referring to the drawings:

Figure 1 represents a front elevation of a dial for a radio condenser, a portion of 35 the device embodying the invention being illustrated associated therewith.

Fig. 2 is a horizontal sectional elevation as taken on the line 2—2 of Fig. 1.

Fig. 3 is a view similar to Fig. 2 but illustrating a modified embodiment of the invention.

Like numerals refer to like parts throughout the several views of the drawings.

In the drawings, referring particularly to Figs. 1 and 2, 4 represents a portion of a front panel of a cabinet in which a radio apparatus of any desired construction is located and mounted. A dial 5 provided with graduations 6 and also having the usual handle 7, through the medium of which the dial is usually rotated, is located upon the exterior of the panel 4, being fast to a shaft 8 which connects with a condenser well known to those skilled in the art.

55 In practically all instances, the dial 5 and handle 7 are either moulded in one piece,

or are so constructed that they form a single unit and the handle 7 is employed to rotate the dial in adjusting the condenser while tuning the instrument. It has been found, 60 however, that when the hand of the operator grasps the handle 7, and in some instances even before the hand has touched the handle, that a confusing noise is produced which renders an accurate tuning of 65 the instrument difficult.

The device of this invention is, therefore, provided for the purpose of rotating the dial 5 without being obliged to touch the handle 7 and is as follows:—Provided in 70 the panel 4 adjacent to the periphery of the dial 5 is an opening 9 into which may be inserted a friction member 10, preferably constructed of rubber or some other suitable flexible insulating material. A portion 75 11 of the friction member 10 is conical-shaped and the periphery of said conical-shaped portion engages the periphery of the dial 6 while the apex portion thereof projects through the opening 9 thereby providing means for positioning the friction member relatively to the dial 5. The friction member 10 is rotated through the medium of a rod 12 preferably constructed of insulating material at the outer end of 80 which is located a handle portion 13. The rod 12 is sufficiently long for the operator to grasp the handle 13 thereof without the hand of the operator being sufficiently close to influence the instrument. A shield 14 constructed of suitable insulating material is mounted upon the rod 12 adjacent to the handle portion 13 thereof and said shield also acts to prevent the hand of the operator from influencing the tuning of the instrument.

In tuning a radio instrument, and particularly when manipulating the dial of the condenser, or other portions of the instrument that are influenced by the presence of 100 the body of the operator, the rod 12 is grasped at the handle portion 13 thereof and the conical portion 11 of the friction member 10 is inserted in the opening 9 of the panel 4 and said friction member is 105 forced into said opening until the periphery of the conical portion 11 engages the periphery of the dial 5. The rod 12 is then rotated in either direction as required to properly adjust that portion of the radio apparatus that is associated with the dial 5. It will be noted that by using a friction 110

member 10 having a relatively short diameter as compared to the diameter of the dial 5, that a much more delicate adjustment may be obtained than is possible by utilizing 5 the handle 7 of said dial.

It will also be noted that as the friction member 10 is constructed of rubber, that the friction between said member and the periphery of the dial 5 may be increased 10 or decreased as desired according to the pressure upon the rod 12 tending to force the latter into the opening 9.

In Fig. 3 a modified embodiment of the invention is illustrated in which a frusto-conical shaped friction member 15 is permanently secured in an opening 16 in the panel 4 adjacent to the periphery of the dial 5. In this form of the device a rod 17 is provided with a shouldered portion 18 and the friction member 15 is rigidly fastened to said rod with one end thereof abutting against the shouldered portion 18 of said rod while the periphery of said friction member 15 contacts with the periphery of the dial 5. The 25 friction member 15 is permanently held within the opening 16 of the panel 4 through the medium of a collar 19 which is detachably secured upon said rod and said collar

bears against the inner surface of the panel 4. The rod 17 is provided with a handle 30 portion 20 and a shield 21 is furthermore mounted upon said rod adjacent to said handle portion 20. The operation of this embodiment of the invention is exactly the same as previously described in connection 35 with the device illustrated in Figures 1 and 2.

I claim:

A device of the character described comprising, in combination, a panel, a dial rotatably mounted on said panel, said panel being provided with an opening therein located adjacent to the periphery of said dial, a flexible friction member positioned on said panel and projecting into said opening and engaging the periphery of said dial and a rod fast at one end thereof to said friction member and embodying therein a handle portion at the other end thereof.

In testimony whereof I have hereunto set 50 my hand in presence of two subscribing witnesses.

THOMAS M. HARRIGAN.
